CARPET.

No. 18,142.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,142, dated March 6, 1888.

Application filed January 26, 1888. Serial No. 262,066. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view 15 of a carpet showing my new design.

My design consists of a number of conventionalized circular flower forms, varying in

size and outline, disposed at irregular intervals over the surface of the carpet. Between these flower forms is an intertwining ribbon-work, consisting of long curving bands or ribbons interlacing with one another, so as to form a sort of net-work. These flower and ribbon forms are arranged upon a damask ground, which appears in the spaces formed 20 here and there by the ribbon-work.

What I claim as new, and desire to secure by Letters Patent, is—

The design for carpets, consisting of the design substantially as shown.

JAS. L. FOLSOM.
